UNITED STATES PATENT OFFICE.

MARVIN PEARCE HATCHETT, OF DURANT, OKLAHOMA.

HEATING APPARATUS.

1,415,345.

Specification of Letters Patent. Patented May 9, 1922.

Application filed March 23, 1920. Serial No. 368,008.

To all whom it may concern:

Be it known that I, MARVIN PEARCE HATCHETT, a citizen of the United States, and a resident of Durant, in the county of 5 Bryan and State of Oklahoma, have invented certain new and useful Improvements in Heating Apparatus, of which the following is a specification.

My invention is an improvement in heating apparatus, and has for its object to provide an apparatus of the character specified, especially adapted for utilizing to the best advantage the heating capacity of an open grate, or the like, wherein cold air is drawn 10 from the outside of the building, heated by the open fire and distributed to the room at the upper portion thereof to thoroughly heat all parts of the room and rooms above the room in which the open grate is located 15 and rooms adjoining the room above, or the upper rooms of a building.

In the drawing:—

Figure 1 is a sectional view of a portion of a house or building showing the apparatus in use, and 25

Figure 2 is a similar view showing another arrangement.

In the embodiment of the invention shown in Figure 1, an open fire, in the present instance, a grate, indicated at 9, is arranged in the usual manner at the bottom of a flue 10 which conducts the smoke to the outer air.

As is known, the only efficient heat of an open fire is radiant heat and but a small percentage of the heat developed is utilized for heating the room in which the open fire is arranged. By far the greatest calorific value of the fuel escapes by the chimney or flue.

In tightly closed rooms, sufficient air does 40 not enter to take the place of the column of air rising through the flue, and there is a tendency to rarefaction of the air in the room. Thus, the approximate equilibrium between the pressure inside and outside the 45 room is disturbed resulting in smoking chimneys, or insufficient draft.

In rooms having many openings, as for instance, cracks about the doors and in the floors, loose fitting windows and the like, the 50 equilibrium of the air pressure within and without is maintained by the disagreeable cold drafts that render it so difficult to keep the room comfortable.

The present invention overcomes this difficulty by adding convection heat to the

room, without appreciably diminishing the radiant heat, thus warming the remote portions of the room where the lines of radiant heat alone could not reach. The incoming air is heated by heat which is ordinarily wasted escaping up the flue to the outside air, and the fuel energy is thus conserved. The invention also comprehends the provision of means whereby not only the room or rooms in which the grate is located may be 60 effectively heated, but rooms above, that is upper rooms and rooms adjoining the rooms above, may also be effectively heated.

With this object in view, I arrange within the flue 10 a pipe 11 of suitable cross section, 70 the said pipe extending to near the burning fuel in the grate at its lower end and to near the ceiling of a room indicated at 14 and 15. This arrangement is for heating more than one room and in the construction, the lower 75 room has a grate 9 arranged at the bottom of the flue 10. The heating pipe 11 which is arranged in the flue and of which there may be one for each room to be heated, extends from near the grate to near the ceiling of the 80 room. The pipe 11 has a lateral inlet 13 at its lower end extending through the flue wall to the outer air, and at its upper end said pipe has a lateral outlet, 14 for the room 12 and 15 for the room 8, the said outlet 85 being near the ceiling of the room.

With this arrangement, a constant circulation of air is maintained, the cold air entering from the outside, being heated in the flue and being delivered at the ceilings 90 of the rooms, from whence it circulates back to the opening in front of the grate 9, and passes upwardly through the flue. The course of the air is indicated by arrows and in addition to the supplying of thoroughly 95 heated air to all parts of the room, the foul air is withdrawn, and a constant circulation of fresh air and heated fresh air being maintained. The heated air which usually passes out of the flue and is wasted, is utilized to 100 heat the incoming air. As is known, warm air rises, while cold air sinks, and the heated air entering at the top of the room, as it cools, tends to sink, and will be drawn out from near the floor, by the pressure through 105 the flue. The pipe 11, and it will be understood that several pipes may be used if desired, provides an open and easy path for the outside air to enter the rooms, to take the place of the partial vacuum produced 110

by the exhaust or draft up the chimney. The chimney is thus free to "draw," and at the same time the cold drafts through the chinks are diminished or eliminated.

5 In order to provide an escape for the foul air in the room 12 an opening 16 is provided near the floor, opening in to the flue, and a pipe 16^a leads from this opening to the outer air, the pipe being capped on top in 10 the usual manner to prevent rainfall from entering the room. This pipe hastens the circulation of the air and avoids interference with the draft of the flue.

With this arrangement the heated air in 15 the pipe 11 is delivered into the rooms 8 and 12 at the ceiling, and circulates in the same manner as described. In each room, the heated air is also delivered at the ceiling and the foul air escapes through the flue by 20 way of the pipe 16^a.

In Figure 2 there is shown an arrangement for heating more than one room as in Figure 1 and also means whereby if it is desired, the room above the room in which the 25 grate is located and adjoining the room 12 on the opposite side thereof from the flue, may also be heated. As shown, the horizontal outlet 14 is extended through the room 12 as indicated at 17 to pass through the 30 room adjoining the room 12, an escape open-

ing 18 being provided for the escape of the foul air.

The pipes will be constructed, in practice, of heavy material and will vary in size, length and number in accordance with the 35 size and position of the rooms to be heated, dampers being provided for reducing or closing the pipes, and the pipes may be in separable sections, or in lengths to suit. They may be built with the chimneys or 40 installed in those already built.

I claim:

A heating apparatus comprising in combination with an open grate and flue thereof, a heating pipe disposed within the flue adjacent the back wall thereof and having its lower end leading through a wall of the building directly to the external atmosphere, an elbow at the lower end immediately above the grate, oppositely extending lateral outlet pipes leading from said heating pipe into the extreme upper portions of the rooms to be heated adjacent to the ceiling thereof, and a ventilator pipe leading into and along the flue from the lower portion of the room 50 above the one in which the grate is located, said ventilator pipe being separate from the flue and of smaller diameter than the heating pipe.

MARVIN PEARCE HATCHETT.
